GOLF GAME PLAYING BOARD

Albert S. Moorman, Kew Gardens, N. Y.

Application January 31, 1950, Serial No. 7,590

Term of patent 14 years

(Cl. D34—5)

To all whom it may concern:

Be it known that I, Albert S. Moorman, a citizen of the United States, residing at Kew Gardens, in the county of Queens and State of New York, have invented a new, original, and ornamental Design for a Golf Game Playing Board, of which the following is a specification, reference being had to the accompanying drawing, forming part thereof.

Fig. 1 is a plan view of a golf game playing board embodying my new design; and

Fig. 2 is a side elevation of the same.

I claim:

The ornamental design for a golf game playing board, substantially as shown.

ALBERT S. MOORMAN.
